CONTROL MECHANISM FOR HONING MACHINES

Harry J. Caldwell, Rockford, Ill., assignor to Barnes Drill Co., Rockford, Ill., a corporation of Illinois

Application February 6, 1943, Serial No. 474,917

5 Claims. (Cl. 51—34)

The invention relates to honing or lapping machines and more particularly to improved control mechanism for such machines.

Machines of the above general character are utilized extensively in dressing both internal and external cylindrical surfaces. Such machines employ a cylindrical tool having a series of abrasive elements mounted for movement radially toward and from the surface to be dressed. In practice, the abrasive elements of the tool are normally held in a retracted position to permit the tool and work to be brought into operative relationship without danger of marring the work or damaging the tool. When the tool and work are properly positioned, tool expansion is initiated, that is, the abrasive elements are shifted radially into engagement with the surface of the work and are forced against the surface with substantial pressure while the tool and work are relatively rotated and simultaneously relatively reciprocated. Relative rotation is continuous in a honing operation and intermittent in a lapping operation.

With the control mechanism heretofore available, considerable time is lost in shifting the abrasive elements from their retracted positions into engagement with the work surface, particularly when the tool expanding mechanism is arranged to effect controlled expansion of the tool, or in other words, to advance the elements at a definite rate so as to maintain a predetermined pressure on the work throughout the operating cycle. With this in view, one object of the invention is to provide improved control mechanism for reducing the time required to condition the tool for actual operation upon the work thereby materially increasing the productive capacity of the machine.

A more specific object is to provide novel control means operable at will by the machine attendant for effecting rapid expansion of the tool when desired without interfering with the controlled expansion of the same during the working portion of the cycle.

Another object is to provide novel means for visually indicating the extent to which the tool may be expanded at any stage of the honing cycle.

Other objects and advantages of the invention will become apparent from the following detailed description of the preferred embodiment illustrated in the accompanying drawings in which:

Figure 1 is a diagrammatic view of a honing

machine embodying the features of the invention.

Fig. 2 is a side elevational view of the tool expanding and control mechanism of the machine.

Fig. 3 is a vertical sectional view of the mechanism shown in Fig. 2.

Fig. 4 is a transverse horizontal sectional view taken along the line 4—4 of Fig. 2 showing also a portion of the machine head to which the control mechanism is attached.

For purposes of illustration, the invention has been shown and will be described herein as embodied in a vertical, multiple spindle, internal honing machine of the type in which the relative rotational and reciprocatory movements of the tool and work are effected by rotating and simultaneously reciprocating the tool while the work is held stationary. A specific type of hone expanding mechanism has been shown by way of illustration, but it is to be understood that the invention is not limited to use with this particular mechanism and that it is also readily applicable to other types of machines. It is also to be understood that various modifications and adaptations may be made in the form, construction and arrangement of the parts without departing from the spirit and scope of the invention as expressed in the appended claims.

Referring now to the drawings, the machine selected to illustrate the invention comprises a head 10 (Figs. 1 and 4) supported and guided by suitable framework for movement toward and from a stationarily supported workpiece W. Journaled in the head with their axes parallel to its reciprocatory path are a plurality of tubular spindles 11 each carrying on its outer end a conventional internal honing tool 12. The spindles are rotatably driven by a suitable prime mover through an elongated spiral toothed gear 13 (Fig. 4) coaxing with spiral toothed pinions 14 fast on the respective spindles.

In the particular machine illustrated, the head is reciprocated by pressure fluid actuated means comprising a piston 20 carried on a rod 21 rigidly anchored to the head. The piston is arranged to work in a cylinder 22 stationarily supported on the framework of the machine. Fluid under pressure is supplied to the cylinder by a pump P under control of a stop valve V and a reversing valve V1. The pump may be of any suitable type and, as herein shown, is provided with an inlet 23 through which fluid is drawn from a sump or reservoir R, and an outlet 24 through which fluid under pressure is directed to

the stop valve V. An electric motor M or other suitable prime mover may be utilized to drive the pump.

The stop valve V is a conventional, two-position, plunger type valve adapted to be operated in any preferred manner. In one position, the valve is effective to direct the fluid delivered by the pump P back to the reservoir R through a return line or drain 25. In the alternate position, the stop valve directs the fluid from the pump P through a pressure line 26 leading to the reversing valve V1. A pressure responsive relief valve 27 connected to the pump outlet 24 acts to maintain the fluid in the system at a predetermined pressure.

The reversing valve V1, also of conventional form, includes a two-position plunger operative to connect the pressure line 26 with either end of the cylinder 22 while connecting the other end of the cylinder to the drain line 25. The plunger of this valve is shifted selectively between its two positions under control of a pilot valve V2 arranged to direct pressure fluid alternately to opposite ends of the valve housing. The pressure fluid supply for this purpose is received through a branch 28 of the main pressure line 26.

The pilot valve is arranged for actuation in response to movement of the head 10, such actuation being effected through the medium of a control rod 30 reciprocable with the head. For this purpose, the control rod carries a series of dogs or stops including upper and lower limit stops 31 and 32 and an intermediate stop 33. The latter, together with stop 32, defines the upper and lower limits of the working stroke of the head in which the tools are traversed axially through the work. Provision is made for shifting the intermediate stop to an inactive position thereby permitting the head to travel beyond the upper limit of the working stroke to the fully retracted position in which the tools are withdrawn from the work. As the head approaches the retracted position, further movement is interrupted by the upper limit stop 31 acting through the pilot valve and other well known control mechanism. The mode of operation of the control mechanism is well known and a detailed description is therefore believed to be unnecessary.

The honing tools 12 may be of any suitable construction and are preferably adapted for power actuation. A tool of this type is disclosed in U. S. Patent 2,271,768 granted February 3, 1942 to A. M. Johnson, to which reference may be had for details of construction. Each tool 12 comprises a cylindrical body in which a series of elongated abrasive elements 35 are mounted for movement radially of the body. The elements are normally held in a withdrawn or "contracted" position by springs (not shown) and are shifted radially outwardly or "expanded" by an axially movable rod 36 extending through the tubular spindle and coacting with cam means enclosed within the body of the tool. Spring means within the spindle normally holds the actuating rod in its upper or tool contracting position.

In the particular form illustrated, the actuating rods 36 of the several tools are extended beyond the inner ends of their respective spindles and into the head 10, as shown in Fig. 1, for cooperation with power driven expanding mechanism carried on the head. This mechanism as herein shown includes a shaft 37 (Figs. 1 and 4) journaled in the head and extending transversely

therethrough above and in alignment with the actuating rods. The shaft is formed with an eccentric cam portion 38 positioned to coact with the projecting ends of the rods 36 and operative to force the rods downwardly for expanding the tools when the shaft is rocked out of the neutral position in which it is shown in Fig. 1.

Power actuated means of any preferred character may be utilized for rocking the actuator shaft 37 to expand the tools 12. As herein shown, the power means provided for this purpose is of the pressure fluid actuated type comprising a piston 40 (Figs. 1 and 3) working in a cylinder 41. The piston is connected by a rod 42 with a bar 43 arranged to shift an actuating member 44 rigidly secured to the tool expanding shaft 37. The actuating member, as herein shown, is in the form of a bell crank having arms 45 and 46 projecting radially of the shaft and substantially at right angles to each other. An operative connection between the bar 43 and the arm 45 of the actuating member is provided by rack teeth 47 formed in one face of the bar and meshing with teeth in a segmental extension formed on the end 25 of the arm 45. The actuating member is non-rotatably anchored to the shaft 37 and held in place thereon by a nut 48 threaded on the reduced end portion of the shaft.

A pump P' of any suitable character, herein shown as driven in tandem with pump P by the motor M, supplies fluid to the tool expanding cylinder 41. In the present instance an accumulator A is associated with the pump in well known manner to provide a substantial volume of fluid under pressure for effecting rapid movements of the actuator and associated apparatus. A control valve V3 is arranged to direct the fluid selectively by way of pipes 50 and 51 to either end of the cylinder 41 while connecting the other end 40 of the cylinder to the drain line 25. A control rod 52, adapted to be rocked about its longitudinal axis in well known manner in response to movements of the head into or out of the working range, is adapted to control the operation of the valve V3 so as to initiate expansion of the tools upon their entry into the work and to effect contraction of the tools prior to their withdrawal from the work.

The pressure of the fluid supplied to the actuator cylinder is determined, in this instance, by one or the other of two conventional pressure relief valves V4 and V5 connected with the outlet of the pump P'. The valve V4 is preferably set to open at the lower working pressure, while the valve V5 is set for the higher working pressure. A shut-off valve V6 is provided for closing the connection between the pump and the valve V4. Thus, when the valve V6 is closed, the pressure in the system is determined by the setting of the high pressure relief valve V5. When the valve V6 is open, low pressure relief valve V4 is in control. The shut-off valve may be operated in any preferred manner.

Provision is made for controlling the rate of expansion of the honing tool by the action of the pressure fluid actuator so as to enable the tool to operate at its most efficient rate. The particular mechanism herein shown for effecting such control comprises a shiftable abutment member 53 arranged to coact with the arm 46 of the actuator and operative to variably limit the extent of movement thereof in a direction to expand the tool. The abutment member is supported for movement transversely of the path described by the arm 46 and the side of the mem-

ber adjacent the arm is formed to provide a control surface 54 inclined with respect to the path of the member. Accordingly, endwise shifting of the member is effective to cause the control surface to advance toward or recede from the arm 46 and thereby determine the extent to which the actuating member may be rocked. To reduce friction, the arm is provided with a roller 55 adapted to engage the control surface.

Shifting of the abutment member 53 may be effected by any suitable means. As herein shown, a pressure fluid operated actuator is provided for shifting the member, the actuator comprising a piston 60 (Figs. 1 and 3) working in a cylinder 61 and connected by a piston rod 62 with the abutment member. A plunger 63, which may be formed integrally with piston 60 if desired, is disposed in the lower end of the cylinder 61 and its presence therein substantially reduces the volume of the cylinder and the area of the piston exposed to fluid action to facilitate rapid return of the piston and associated parts to the upper or rest position.

In the particular form of the mechanism illustrated, the tool expanding cylinder 41 and the expansion control cylinder 61 are formed in a common cylinder block 65 adapted to be bolted or otherwise rigidly secured to the top of a housing 66 enclosing the bar 43, abutment 53 and associated elements. The housing may be integral with or rigidly secured to the side wall of the head 10 as shown in Fig. 4.

In order to coordinate the movements of the abutment member 53 with the operation of the rack bar 43, the cylinders 41 and 61 are preferably connected parallel to a common pressure fluid source. As shown in Figs. 1 and 3, the pipe 50 leading from the valve V3 is arranged to open into a passage 67 in the cylinder block 65 having one branch 68 leading to the upper end of the cylinder 41 and a second branch 69 leading to the corresponding end of the cylinder 61. An orifice valve 70 of any suitable construction adapted to be adjusted by means of a hand lever 71 is interposed in the branch passage 69 for regulating the rate of fluid flow into the cylinder 61. It will be understood, of course, that the orifice valve may be interposed in the exhaust passage leading from the lower end of the cylinder 41. In either instance, by appropriate setting of the orifice valve, the advance of the piston 60 and the abutment member 53 may be timed as required for each particular job.

The lower ends of the cylinders 41 and 61 are likewise connected in parallel, in this instance, by a passage 72 in the cylinder block. Accordingly, in the downward movement of the pistons 40 and 60, fluid is exhausted from both cylinders through the pipe 51 and returned to the reservoir by way of the valve V3 and drain line 25. When the valve V3 is reversed to direct pressure fluid through the pipe 51, both pistons are forced upward. Fluid is exhausted from the cylinder 61 through a passage 73 and check valve 74 which provide a one-way by-pass around the orifice valve. The check valve, herein shown as a spring pressed ball type valve, prevents fluid flow through the passage 73 into the cylinder, thus forcing the fluid to pass through the orifice valve as previously described. The passage 73 communicates with the main passage 67 of the cylinder block so that exhaust fluid from the cylinder 61 together with the fluid exhausted from the cylinder 41 returns to the reservoir by way of the pipe 50, valve V3, and drain line 25.

In a honing operation, the rate of expansion of the honing tool is limited by the rate at which stock is removed from the surface of the work. Under the most favorable conditions the rate of expansion is relatively slow and, when controlled expansion is employed, as in the exemplary machine, expansion is further restricted by the abutment member so as to maintain the pressure of the abrasive elements on the work substantially uniform and below the point at which the elements of the tool tend to become loaded with abraded material. In practice, the orifice valve 70 is therefore set to pass a very small quantity of pressure fluid into the cylinder 61 and the rate of movement of the abutment member 53 is consequently quite slow.

At the beginning of each honing cycle the honing tool is fully contracted, that is, the abrasive elements are withdrawn to their inactive positions in order to facilitate entering the tool in the work. The abutment member 53 is likewise held in the retracted position in which it is shown in Fig. 3. In this position, the highest point of the control surface 54 is disposed in the path of the roller 55 on the crank arm 46. When pressure fluid is initially introduced into the cylinder 41 to start the honing operation, piston 40 shifts the bar 43 downwardly and rocks the actuator 44 in a clockwise direction (as viewed in Fig. 3) until the roller 55 engages the control surface 54 thereby preventing further movement of the actuator. This initial rocking of the actuator partially expands the honing tool, but further expansion is required to bring the abrasive elements into operative contact with the surface of the work. The extent of this further expansion varies with different workpieces and may at times require a preliminary shifting of the abutment member through substantially one-half of its full working stroke.

In order to avoid the loss of time that would result from effecting this preliminary shift of the abutment member under the action of the expansion control mechanism above described, the invention provides auxiliary control means operable at will to effect a rapid shifting of the abutment member independently of such control mechanism. The auxiliary control means, as constructed for use with expansion control mechanism of the type herein disclosed, is in the form of a pressure fluid circuit including a normally closed shut-off valve V7 arranged to by-pass the orifice valve 70 and deliver an unrestricted flow of pressure fluid to the upper end of the cylinder 61.

Referring to Fig. 3, the valve V7, as herein shown, comprises a housing 75 formed with a central passage 76 having inlet and outlet ports 77 and 78. Inlet port 77 is connected by a pipe 79 with the main pressure fluid passage 67 in the cylinder block 65 to receive pressure fluid from the pipe 50. Outlet port 78 of the valve is connected by a pipe 80 with a port 81 communicating with the upper end of the expansion control cylinder 61. Communication between the inlet and outlet ports of the valve is normally prevented by a valve member, herein shown as ball 82, yieldably held against its seat by a spring 83. When the valve member is shifted away from its seat (to the left as viewed in Fig. 3) fluid flows unrestrictedly through the pipe 79, the valve passage 76 and the pipe 80, into the upper end of the cylinder 61, thus rapidly shifting the piston 60 and abutment member 53 toward the tool expanding position.

While any suitable means may be utilized for opening the valve **V7**, it is preferred to employ a remotely controlled actuator for this purpose. The valve actuator, as herein shown, comprises a cylinder **84** suitably supported at one end of the valve body **75**. Fitted within the cylinder is a piston **85** having a piston rod **86** extending through the valve body and into the passage **76** to coact with the valve member **82**. To shift the piston **85**, a fluid medium such as compressed air is introduced into the outer end of the cylinder **84** through a pipe **87** in which is interposed a manually operable valve **V8** located at any point conveniently accessible to the machine attendant.

The valve **V8** may be of any suitable construction and is preferably arranged to vent the pipe **87** to the atmosphere when in its normal or unoperated condition. This permits the piston **85** to return to rest position at the right end of the cylinder under the influence of the spring **83** acting through the valve member **82** and piston rod **86**. Operation of the valve **V8** closes the vent and connects the pipe **87** to the compressed air line thus directing compressed air to the cylinder **84** with a resultant shifting of the piston **85** to the left. Valve member **82** is thereby moved to the open position to establish the by-pass circuit as above described.

In order to enable the machine attendant to accurately adjust the expansion control mechanism, means is provided for visually indicating the maximum degree of expansion permitted the honing tool at any time. The indicating means, as herein shown, comprises a pointer **88** carried on the outer end of a shaft **89** journaled on a cover plate **90** forming one side of the housing **66**. The pointer is arranged to sweep over an arcuate scale **91** graduated to show the expansibility of the honing tool in any suitable units.

Means is provided for driving the pointer carrying shaft in timed relation with the shifting of the abutment member **53** so that the position of the pointer is accurately coordinated at all times with that of the member. The driving means, as shown in Fig. 4, preferably comprises a gear **92** pinned to the inner end of the shaft **89** and adapted to mesh with a pinion **93** fast on the reduced end portion of a horizontal shaft **94** extending through the housing **66** adjacent the abutment member **53**. The shaft **94** is journaled in suitable bearings carried on the housing **66** and cover plate **90**. Keyed to the shaft intermediate its ends is a pinion **95** meshing with the teeth of the rack member **96** removably attached to the front face of the abutment member **53**. The shaft **94** also carries a roller **97** positioned for engagement by the surface of the abutment member opposite the control surface **54**. The roller thus serves to support the member and absorb the thrust of the actuator **44** thereon.

Due to the direct rack and pinion connection between the abutment member and the shaft **94** and the gear connection between the latter and the pointer shaft **89**, the pointer **88** is invariably rocked through an angle proportionate to the displacement of the abutment member from the normal rest position. As the spacing of the control surface from the actuator **44** is dependent upon the position of the abutment member, the pointer is thus effective to indicate the maximum sweep permitted the actuator and therefore the maximum expansibility of the honing tool.

It will be apparent from the foregoing that the invention provides control mechanism of a novel and advantageous character for use with honing

tool expanding mechanism of the controlled expansion type. The invention permits the rapid expansion of the honing tool to bring the abrasive elements thereof into working contact with the work surface without the loss of time experienced when expansion is effected solely by the controlled expansion mechanism. The invention also provides novel means for visually indicating the maximum extent to which the tool may be expanded at any stage of the honing cycle, thus permitting quick and accurate adjustment of the control mechanism to meet a wide variety of working conditions.

I claim as my invention:

1. Mechanism for actuating an expandable and contractible honing tool comprising, in combination, an actuating member movable in one direction to expand the tool and in the opposite direction to contract the tool, power actuated means for imparting movement to said actuating member, a shiftable abutment supported for movement transversely of the path of said actuating member, said abutment having a control surface inclined with respect to its path of movement and positioned for engagement by said actuating member, a pressure fluid actuator operable to shift said abutment and thereby cause the control surface to recede from the actuating member, means for supplying pressure fluid to said actuator, a control valve operative to regulate the flow of pressure fluid to said actuator and thereby determine the rate of recession of the control surface from the actuating member, and other valve means operable to by-pass said control valve and thereby increase the rate of recession of the control surface from the actuating member.

2. Mechanism for actuating an expandable and contractible honing tool comprising, in combination, an actuating member adapted to be rocked in one direction to expand the tool and in the other direction to contract the tool, a pressure fluid operated actuator arranged to rock the member, an abutment supported for movement transversely of the path described by the actuating member when the latter is rocked in said one direction, said abutment having a control surface adapted to be engaged by said actuating member and inclined with respect to the path along which the abutment is moved, a second pressure fluid operated actuator operative to shift the abutment in a direction to cause the control surface to recede from the actuating member, control means associated with said second actuator normally operative to limit the movement of the abutment to a predetermined rate, and other control means operable at will to condition said second actuator for shifting the abutment at a substantially faster rate than permitted by said first mentioned control means.

3. Mechanism for actuating an expandable and contractible honing tool comprising, in combination, an actuating member movable in one direction to expand the tool and in the opposite direction to contract the tool, power actuated means for imparting movement to said actuating member, a shiftable abutment supported for movement transversely of the path of said actuating member, said abutment having a control surface inclined with respect to its path of movement and positioned for engagement by said actuating member, means operative to shift said abutment and thereby cause said control surface to recede from the actuating member, a control device associated with said shifting means adapted to limit the recession of said control surface to a prede-

terminated rate, and control means operable at will to render said control device temporarily ineffective and thereby increase the rate of recession of said control surface.

4. Mechanism for actuating an expansible and contractible honing tool comprising, in combination, a member movable in one direction to expand the tool and in the opposite direction to contract the tool, power actuated means for moving said member in said one direction, abutment means positioned for engagement by said member to limit the advance thereof in said one direction, power actuated means normally operative to withdraw said abutment means from said member, a control device associated with said power actuated means adjustable to limit the withdrawal of the abutment means to a predetermined rate and thereby permit the member to advance at a corresponding rate, and control means operative to initiate an increase in the rate of with-

drawal of the abutment means without disturbing the adjustment of said control device.

5. Mechanism for actuating an expansible and contractible honing tool comprising, in combination, a member movable in one direction to expand the tool and in the opposite direction to contract the tool, power actuated means for moving said member in said one direction, abutment means positioned for engagement by said member to limit the advance of the member in said one direction, control means operable to effect a gradual withdrawal of the abutment means from said member to permit a corresponding gradual advance of the member, other control means operative to effect a more rapid withdrawal of said abutment means, and means for rendering one or the other of said control means operable selectively.

HARRY J. CALDWELL.
